(57) **CLAIM**

The ornamental design for an in-vehicle controller, as shown and described.

DESCRIPTION

FIG. 1 is a perspective view from the front and top of an in-vehicle controller, showing our new design;

FIG. 2 is a perspective view from the rear and top of the in-vehicle controller;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines showing portions of the in-vehicle controller form no part of the claimed design.

1 Claim, 8 Drawing Sheets(56)
